UNITED STATES PATENT OFFICE.

NELS H. NELSON, OF DES MOINES, IOWA.

AWNING.

Application filed June 13, 1927. Serial No. 198,625.

The primary object of this invention is to provide an improved construction for a roller mounted awning adapted to be stored in a housing at the top of a window opening 5 or the like when not desired for use and arranged for different positions of adjustment so that it may be variably positioned for shade and for storm protection and for covering a screen or window glass and also 10 for controlling ventilation.

A further object of the invention is to provide improved bracket means for supporting a housing adapted to contain a flexible element such as an awning and also 15 means for locking the housing in the supporting bracket.

Another object of the invention is to provide an improved supporting means for the housing, which supporting means also constitutes a cap for closing the end of the 20 housing and for providing ventilating means to the housing.

Still another object is to provide improved means for locking together the walls of a 25 housing across a longitudinal slot therein, thereby reducing the cost of manufacture and also permitting access to the housing at any time without injuring or mutilating the parts thereof, for the purpose of making 30 repairs to the roller mounting or for replacing the flexible member carried thereby.

A further object is to provide an improved binder strip for the lower edge of the awning, which strip also constitutes a means for 35 removably receiving the central part of the U-shaped yoke which controls the movement of the outer edge of the awning, said binder strip also being arranged for covering and closing the longitudinal slot in the housing 40 when the awning is stored therein.

Another object is to provide an improved joint between the awning cloth and the binder strip which is waterproof and dirt-proof and arranged to shed water and to 45 prevent the lodgement of foreign substances.

Another and further object is to provide means for detachably connecting a fringe or like ornamental strip to the outer edge 50 of the awning, said means including an attaching clip which also serves as a wear plate or bumper to prevent the cloth from rubbing on the housing when the awning is stored therein.

Yet another object of the invention is to

provide an improved construction for a 55 spring bumper means which is designed to throw the awning frame past center and facilitate the operation of withdrawing the awning from the housing; said spring means also being utilized for holding tubes in upright position during installation of the awning and thereby facilitating this operation. 60

Another object is to provide improved snap hooks for connecting the controlling ropes to the awning frame and for holding 65 the binder strip in proper position relative to the U-shaped frame.

A further object is to provide an improved double pulley for the controlling ropes which has its casing notched at the ends to reduce 70 friction on the ropes and also arched upwardly in the center to reduce friction on the ropes as they are being paid out while the awning is being raised.

With these and other objects in view, my 75 invention consists in the construction, arrangement and combination of elements hereinafter set forth, pointed out in the claims and indicated by the accompanying drawings in which:

Fig. 1 is a perspective view illustrating my 80 improved awning installed for practical use on a window frame and showing the awning partially withdrawn from the housing for the purpose of shading the window opening. 85

Fig. 2 is an end view of the elements shown in Fig. 1, the awning being stored in the housing.

Fig. 3 is a detail side elevation illustrating 90 the manner in which the spring bumper means engages one of the tubes for holding it in upright position during the operation of installation.

Figs. 4, 5 and 6, are diagrammatic side 95 views showing the awning in different positions; Fig. 4 showing the awning partly withdrawn, Fig. 5 showing it in the ordinary position for shading a window opening, and Fig. 6 showing it extended entirely across the opening in a substantially vertical plane. 100

Fig. 7 is a detail sectional view on the line 7-7 of Fig. 1, showing one arm of the U-shaped yoke slidably received in one of the tubes. 105

Fig. 8 is a perspective view of one end portion of the housing and illustrating particularly the method of locking the hous-

ing walls together across the longitudinal slot through which the flexible member is extended.

Fig. 9 is a perspective view illustrating one end portion of the housing and one of the bracket supports for receiving the same.

Fig. 10 is a perspective view of the key employed for locking the housing walls, as illustrated in Fig. 8.

Fig. 11 is a cross section through the housing on the line 11—11 of Fig. 1, showing the flexible member stored therein and the manner in which the binder strip seals and closes the longitudinal slot of the housing.

Fig. 12 is a detail section on the line 12—12 of Fig. 1, showing the method of attaching the flexible member to the binder strip.

Fig. 13 is a detail section on the line 13—13 of Fig. 1 and showing the method by which the snap hook of the controlling rope engages the central part of the U-shaped frame through a notch in the binder strip.

Fig. 14 is a detail perspective view of a portion of the binder strip having a notch therein and also a slit for receiving the clip which is employed to attach the fringe to the binder strip.

Fig. 15 is a detail section on the line 15—15 of Fig. 1, showing particularly the method of attaching the fringe to the binder strip.

Fig. 16 is a perspective view of one of the clips employed for attaching the fringe or other ornamental strip.

Fig. 17 is an elevation of a pulley employed for receiving and fastening the controlling ropes.

In the drawings, I have employed the numeral 20 to designate generally, a sheet metal housing for the awning, which housing is designed to be mounted at the top of a window frame 21 or the like. The housing 20 is formed of a sheet of metal bent into substantially square form in cross section. The bottom wall 20' and front wall 20" are formed from the opposite side marginal portions of the sheet and do not quite abut at their edges but are slightly spaced apart to form a slot 22 which extends longitudinally of the housing at the lower forward corner thereof. Mounted across the interior of the housing and spaced somewhat from the respective ends thereof, are flanged partitions 23. A roller 24 is mounted for rotation centrally of the housing 20 and has its end portions journaled in the partitions 23. A flexible awning member 25 such as a piece of canvas or the like is attached at one end of the roller 24 and is adapted to be extended through the slot 22 of the housing at times. The roller 24 is provided with a spring 26 which tends to

rotate the roller in one direction so as to wind the awning 25 thereon.

Heretofore, it has been the custom to mount housings such as 20 containing roller mounted flexible members directly upon a structure such as the window frame 21 by means of screws or other fastening members passing through one or more walls of the housing between the partitions such as 23 and the ends of the walls, all of the walls being rigidly attached to the partitions by spot welding or other suitable means. Under such construction, the spot welding of the forward and bottom walls of the housing would not be applied until after the flexible member on its roller had been mounted in the housing and the spring tension of the roller had been adjusted to suit the particular need, after which the spot welding would be applied to rigidly secure the forward and lower walls of the housing. In the event it became necessary to remove the roller for repairs or readjustment of the tension or for replacing the flexible member, it was then necessary to apply force sufficient to detach the forward and bottom walls from the partitions in order to enlarge the longitudinal slot by outward bending of said walls somewhat as indicated by dotted lines in Fig. 8. This operation

not only required considerable work, but also resulted in greater or less distortion of some of the members of the housing and in some instances, in such injury as to require the replacement of the entire housing.

In addition to this difficulty, it was also more or less troublesome to mount the housing by the method I have mentioned. To overcome these difficulties and to facilitate the installation of the housing and also its removal and manipulation for purposes of repair or the like, I have provided a new method of supporting the housing by means of separate brackets and also a new method of detachably securing the forward and bottom walls of the housing.

By my improved method, the bottom wall 20' and forward wall 20" are not rigidly attached to the partitions 23. Metal loops 27 are formed on the inner faces of these walls in a vertical plane between each partition 23 and the adjacent free ends of the walls, as clearly shown in Fig. 8. These loops may be produced by forming parallel slits in the metal of the walls and pressing the material between the slits inwardly. A key 28 is formed from a strip of metal having its end portions tapered and bent at right angles to the strip in planes perpendicular to each other. This key, which is shown in detail in Fig. 10, is employed to lock the walls 20' and 20" together by insertion of the tapered ends within the loops 27 of said walls, the body of the key extending across the corner of the housing and

over the slot 22 as shown in Fig. 8. One of these keys is employed at each end of the housing and they are inserted after the roller carrying the flexible member has 5 been mounted in the housing. Should occasion ever require the removal of the roller and flexible member from the housing, the keys 28 may be readily removed and the walls 20' and 20" spread apart sufficiently 10 to permit the passage of the roller and flexible member without causing any damage to the housing. When the keys are inserted, the tapered shape of their ends by engaging the loops 27 serve to draw the walls 20' and 15 20" tightly against the margins of the partitions 23. As here shown, the loops 27 of the housing walls are projected through slots 27' formed in the flanges of the partition members. The top and rear walls of 20 the housing are rigidly attached to the flanges of the partitions 23 by means of 25 spot welding at the points 29.

For the support of the housing on a frame such as 21, I have provided yoke-shaped 30 brackets 30, one of which is clearly shown in Fig. 9. Each bracket 30 is formed with screw holes 31 in its central portion by means of which it may be rigidly attached and it may also have similar holes 31 in its 35 top and bottom members if desired for convenience in mounting in certain locations. The brackets 30 are of a shape to fit snugly the outside of the housing 20 and preferably engage said housing near its respective ends 40 and adjacent the partitions 23. The ends of the brackets 30 are rolled outwardly to form eyes 32, which eyes project beyond the forward margin of the housing. A key 33 is formed of a piece of wire or light rod 45 having its end portions bent at right angles and adapted to be inserted in the upper and lower eyes 32 of the bracket to prevent outward movement of the housing from the bracket after it is installed therein, said key 50 then extending across the front of the housing. Each bracket 30 also includes an end wall 34, formed integrally with the central portion of the bracket and bent into a plane coinciding with the outer margins of the end 55 members of the bracket but not attached thereto. The end walls 34 of the brackets serve to close the ends of the housing when the housing is installed in the brackets and thereby eliminate the need of using separate 60 caps. To securely hold the key 33 in the eyes 32 of the bracket, a latch member such as 35 may be carried by the forward margin of the end wall 34 and arranged to engage said key after it is placed in position. In 65 the present instance, I have shown the latch 35 as composed of a piece of wire bent to form a portion journaled in an eye 36 or bearing formed on the forward margin of the end wall. The body portion of the latch 35 is then turned outwardly in a hori-

zontal plane and is adapted to be swung across the open end of the support 30 and is also bent to form a lip 37 to frictionally engage the key 33 and hold the same in place as indicated in Fig. 1. It is obvious 70 that other forms of latching means for the key may be employed if desired. The end walls 34 may also be provided with the screw holes 31 if desired as it may be convenient at times to mount the supports 30 75 by means of screws extending through said member.

It is desirable to provide means for the circulation of air through the housing to dry out the flexible member 25 after it has 80 become damp and prevent molding or other deterioration. This may conveniently be done by extending the openings in the partitions 23 to form elongated slots 38 and also by providing openings 39 in the end 85 members 34 of the supports. The openings 38 and 39 preferably are staggered so as to prevent the entrance of rain or snow to the interior of the housing.

A binder strip is provided for the outer 90 margin of the awning cloth 25, which strip is composed of sheet metal extending the full length of the cloth and bent at one marginal portion to form a hook or trough 95 40 which preferably is rectangular in cross section as shown in Figs. 13, 14, and 15, said trough being located on the rear side of the device or the side toward the window frame 21. The opposite marginal portion of the binder strip is bent to form a fold 100 41 substantially parallel and spaced forwardly from its body and at its extreme margin again bent inwardly and upwardly to form a flange 42 located between the body and the fold 41 and spaced from both, as 105 shown in Fig. 12. The outer or free margin of the awning cloth 25 is doubled upwardly and forwardly upon itself and this doubled portion is then folded rearwardly and secured together by a line of stitching 110 43 spaced slightly from the inner fold 44 of the cloth. The folded portion of the binder strip is then caused to engage the rearwardly folded portion of the cloth and extend around such portion with the flange 115 42 engaging between the line of stitching 43 and the innermost fold 44 of the cloth, as shown in Fig. 12. Thereafter, a slight pressure is applied to the folded portion of the binder strip to compress it upon the 120 folded portion of the cloth and thereby cause a permanent connection between the metal and cloth. A longitudinal bend or angle 46 is produced in the binder strip at a point adjacent the lower margin of the 125 cloth so that the hooked part of the strip projects forwardly of the plane of the body of the cloth. By this arrangement, any water which may fall upon and run down the awning cloth is projected beyond the 130

joint between the cloth and metal and the seam between said members is rendered waterproof and dirt-proof.

I provide a yoke-shaped frame, preferably made of a rod suitably bent and having its central member 47 received within the rearwardly turned hook 40 of the binder strip which hook preferably has some resiliency and has a tight fit on said rod so that it will not be readily removed therefrom.

Secured to each side of the window frame 21 at a point spaced materially below the housing 20 is a bracket hinge 48 having an inwardly projecting stud 49. Pivoted on the stud 49 of each hinge on either side of the frame is a tubular member 50 which is open at both ends. The arms 51 of the U-shaped frame heretofore referred to, are slidably received in the tubular members 50 and the free ends of said arms are limited in their movement into the tubes by the studs 49.

Suitable cords or ropes 52 are provided for controlling the movement of the awning and its position and I have here shown two of such ropes, one at each side of the awning. Each rope 52 has attached to its upper end, a hook 53 adapted to engage the rod 47 through a notch 54 in the hook portion 40 of the binder strip. The hooks 53 frictionally engage the rod 47 so that they are not readily removable therefrom. This provides a detachable connection of the ropes to the awning structure and also serves to hold the binder strip against longitudinal movement on the rod 47. The ropes 52 extend through pulleys 55 mounted at the lower portion of the window frame and thence extend inwardly toward the median line of the frame. Mounted on the outer central portion of the window sill is a pulley housing 56 which is open at its forward and rear sides and carries two pulleys 57 arranged side by side on vertical pivots. The ropes 52 extend around the pulleys 57 and then inwardly side by side across the window sill. The end walls of the pulley housing 56 are notched on their outer sides at 58 to permit the passage of the ropes without frictional engagement with said walls. The housing 56 also is arched upwardly at 59 in its central portion to permit the ropes 52 to travel in superposed relation at times as they have a tendency to do when the awning is being contracted rapidly into the housing by uncontrolled action of the spring roller. Mounted on the inner central portion of the window sill is a pulley bracket 60 having a pulley 61 pivoted therein on a horizontal axis transversely of the window frame. The pivot of the pulley 61 preferably is a pin 62 which projects a material distance at each side of the bracket and provides a

means for coiling the ropes 52 thereon for the purpose of retaining the awning in any position of extension which may be desired. Both ropes 52 are extended beneath the pulley 61 and arranged as clearly shown in Fig. 1 for control of the awning by a person located within the building of which the window frame 21 forms a part.

The lower wall 20' of the housing preferably is turned downwardly at the margin of the slot 22 to form a flange 63 extending longitudinally of the housing and the forward wall 20" preferably is folded and turned outward slightly as a bead 64. When the awning is contracted within the housing and rolled upon the roller 24 the binder strip on the free edge of said awning engages the bead 64 and the hooked portion 40 of said strip engages behind the flange 63, thereby practically closing the slot 22, as best shown in Fig. 11 and preventing the entrance of rain, snow, or sleet to the housing. It will be understood that normally, the spring of the roller 24 will hold the awning 25 wound on the roller with the binder strip projecting partially within the casing and partially outside, in embracing relation to the flange 63.

When the awning is wound on the roller and the parts are positioned as shown in Fig. 2, the position of the rod 47 in the hooked portion 40 of the binder strip is in a vertical plane outside of the plane of the pulleys 55. It will thus be seen that when draft is applied to the ropes 52 and they are drawn inwardly across the window sill and through the pulley devices 60 and 56, there will be a tendency to swing the rod portion 47 of the U-shaped frame outwardly and downwardly. The arms 51 of the U-shaped frame slide in the tubes 50 as the portion 47 travels in a curved path relative to the window frame. This operation of course, withdraws the awning from the housing and it may be stopped and held in any position of such travel by securing the ropes 52. The outer end of the awning will be held away from the window by the tubes 50 and the fabric 25 will at all times be held taut by the tension of the spring roller. Ordinarily the arms 51 project into the tubes as far as they will go except when the awning approaches its upward limit of movement as it is being wound into the casing or as it approaches its downward limit of movement as hereinafter described. Three positions of such travel are indicated by the diagrams in Figs. 4, 5, and 6. Fig. 4 shows a position which is attained a short time after the above movement is started and Fig. 5 shows a position where the awning is in one of its most useful arrangements for providing shade for the window, although the movement may be continued until the tubes 50 are practically horizontal if de-

sired. Fig. 6 shows a position wherein the awning has been pulled clear down and extends entirely across the window opening in a substantially vertical plane. It will be noticed that after the rod 47 and tubes 50 have reached a certain point in their arcuate travel the rods 51 will again slide outwardly of the tubes until they reach the position of Fig. 6, which outward movement will of course, vary with the vertical dimension of the window frame and the vertical spacing of the hinge brackets 48 above the window sill. The parts are so arranged that the arms 51 can never be wholly withdrawn from the tubes 50 in such movement.

I have also provided an improved cushioning and anti-rattling means for the awning frame, which is shown in Figs. 1, 2, and 3. This means comprises a spring 65 attached to each side of the window frame 21. The springs 65 are located just above the hinge brackets 48 and may be secured and held behind said brackets, as shown. Each spring 65 has a coil 66 between its ends engaging the window frame and above said coil the spring is inclined outwardly from the frame and formed with a curved portion 67 or seat to engage one of the tubes 50. It is desirable to form each spring 65 of parallel lengths of wire and to have said parallel portions separated at their upper ends and each formed with a transverse seat portion 67. As the awning is drawn upwardly, the tubes 50 approach the window frame and are caused to engage the seats 67 of the cushioning springs which take the impact of said tubes if the ropes 52 should happen to be released and the spring roller allowed to draw up the awning and the frame so rapidly that the momentum would swing the tubes against the window frame. When the awning is drawn entirely within the housing the springs 65 are placed under some tension by pressure of the tubes 50 against them. The result of this tension is to cause an outward pressure upon the tubes 50 so that when draft is first applied to the ropes 52 to pull the awning out of the housing, the springs act to push the tubes 50 away from the window frame and thus assist in the operation, as indicated in Fig. 4. The tension of springs 65 also serves to prevent vibration and rattling of the parts.

The springs 65 have another function which is illustrated in Fig. 3. In the operation of installing the awnings, it is necessary to hold the tubes 50 in upright position and then insert the ends of the rods 51 therein, which might require the services of two workmen, particularly if the window is a wide one. By separating the free ends of the springs 65, I am enabled to snap one of the spring portions around the outer face of each tube 50, as shown in Fig. 3, whereby the tubes are yieldingly held in upright

position until the installation is completed. After that, the springs 65 are returned to their normal positions, thus releasing the tubes for their pivotal movement.

It is sometimes desirable to provide an ornamental strip for the free edge or outer end of the awning, which strip may be in the nature of a fringe or scallop. It is not desirable however, to have such ornamental strip permanently attached to the awning because it could not be received within the housing when the awning is wound up and consequently would become soiled more quickly than the body of the awning. By making it detachable, the ornamental strip may be removed and cleaned at any time and also may be removed during winter months when the awning is not used extensively. An ornamental strip of the character described is indicated by the reference numeral 68 in Figs. 1, 2, and 15. For detachably securing the strip 68, I employ a number of clips 69, one of which is shown in Fig. 16. Each clip 69 comprises a short strip of metal having a tongue 70 punched in one end and pressed from the plane of the clip. At intervals, the upper face of the hooked portion 40 of the binder strip of the awning is provided with slots 71 each adapted to receive a tongue 70 of one of the attaching clips. To attach the strip 68, it is laid along the upper face of the binder strip and the clips 69 are applied by pressing their tongues 70 through the material of the ornamental strip 68 and through the slots 71 of the binder strip and then clinching them on the rear face thereof. The ornamental strip 68 preferably extends at its upper margin against the lower looped portion of the body of the awning so that there is no space between said members and the clips 69 serve to hold the strip 68 firmly in place extending over the binder strip of the awning and hanging down over the front edge thereof. The clips 69 also serve to protect the ornamental strip 68 from actual contact with the bead 64 of the housing when the awning is wound on the roller. As shown in Fig. 16, each clip 69 may be formed with a tongue 70 at each end but one of the tongues is not bent out of the plane of the clip until it is required for use in the event the other is broken or bent out of shape in use.

It is apparent that I have provided an efficient awning which is simple of construction and installation and effective in use for covering a window opening or the like and one which is provided with ample means for protecting its parts, particularly when not in use. As the awning fabric is entirely withdrawn within the housing, it is apparent that the awning may be left in place permanently, thus doing away with the necessity of seasonally removing and replacing

it. I have also provided effective means for overcoming many of the difficulties which have heretofore been encountered in the manufacture, installation and use of a device of this kind, as herein pointed out.

It is my purpose to cover by my claims, any modified forms of structure or use of mechanical equivalents which may be reasonably included within their scope and 10 within the scope of my invention.

I claim:

1. In a device of the class described, a housing formed with a longitudinal slot, partitions extending across said housing 15 near the ends thereof and arranged to support a roller, the walls of the housing adjacent said slot being detached with respect to said partitions whereby they may be bent outwardly of their normal positions for enlarging said slot to facilitate removal and 20 replacement of said roller, and locking means adapted to extend across said slot into engagement with the housing walls on opposite sides thereof to hold them in their 25 normal positions.

2. A device of the class described, comprising a housing, two of the walls of said housing being spaced apart at their adjacent margins to form a slot longitudinally of the 30 housing, partitions extending across the housing near the ends thereof and rigidly attached to the other walls of the housing and arranged to support a roller, the housing walls adjacent said slot being detached 35 with respect to said partitions whereby they may be sprung away from the margins of the partitions at times for enlarging said slot to facilitate removal and replacement of the roller, and a key adapted to extend 40 across said slot into engagement with the detached housing walls for holding them in their normal positions.

3. A device of the class described, comprising a housing, two of the walls of said 45 housing being spaced apart at their adjacent margins to form a slot longitudinally of the housing, partitions extending across the housing near the ends thereof and rigidly attached to the other walls of the housing 50 and arranged to support a roller, the housing walls adjacent said slot being detached with respect to said partitions whereby they may be sprung away from the margins of the partitions at times for enlarging said 55 slot to facilitate removal and replacement of the roller, said detached walls having loops on their inner margins outside of said partitions, and a key adapted to extend diagonally across that corner of the housing 60 containing said slot and having tapered portions for insertion in the loops of said housing walls for drawing and holding them in their normal positions.

4. In a device of the class described, a 65 housing, U-shaped supporting brackets cor-

responding in size and shape with the cross sectional area of the housing and adapted to receive and support the same, and latching means extending across the open side of each U-shaped bracket to prevent removal 70 of the housing therefrom.

5. In a device of the class described, a housing, U-shaped supporting brackets corresponding in size and shape with the cross sectional area of the housing and adapted to 75 receive and support the same, each U-shaped bracket being formed at its ends with eyes projecting beyond the housing, and a locking key having portions arranged for insertion in said eyes to prevent removal of 80 the housing from said brackets.

6. In a device of the class described, a housing, U-shaped supporting brackets corresponding in size and shape with the cross sectional area of the housing and adapted to 85 receive and support the same, an end wall integrally formed on the central portion of each U-shaped bracket and designed to provide an enclosure for one end of said housing, and latching means extending across 90 the open side of each U-shaped bracket to prevent removal of the housing therefrom.

7. In a device of the class described, a housing, U-shaped supporting brackets corresponding in size and shape with the cross sectional area of the housing and adapted to receive and support the same, each U-shaped bracket being formed at its ends with eyes projecting beyond the housing, a locking key having portions arranged for insertion in 95 said eyes to prevent removal of the housing from said brackets, an end wall integrally formed on the central portion of each U-shaped bracket and designed to provide an enclosure for one end of said housing, and latching means carried by the free margin of said end wall for engaging said key and 100 holding it in place.

8. In a device of the class described, a housing formed with a longitudinal slot, said housing being formed with rigid partitions near its ends, a removable cap member for each end of the housing, and staggered ventilating openings in the caps and partitions for admitting currents of air to the housing 110 and yet preventing the entrance of rain and snow thereto.

9. In a device of the class described, having a roller mounted flexible element and a swinging U-shaped frame, a binder strip attached to the free margin of said flexible element, said binder strip being formed with a rearwardly directed longitudinal hooked portion adapted to receive the central portion of said U-shaped frame.

10. In a device of the class described having a roller mounted flexible element and a swinging U-shaped frame, a binder strip attached to the free margin of said flexible element, said binder strip being formed with a 120 125

rearwardly directed longitudinal hooked portion adapted to receive the central portion of said U-shaped frame, and a draft element having a hook at one end, a notch in the hooked portion of the binder strip through which the hook on said draft element may engage the central portion of said U-shaped frame.

11. In a device of the class described including a flexible element and a pivoted U-shaped frame, a binder strip attached to the free margin of said flexible element, said binder strip being formed with a rearwardly directed longitudinal hooked portion adapted to receive the central portion of said U-shaped frame, said binder strip having its opposite portion folded around the free marginal portion of the flexible element and being bent outwardly longitudinally immediately below said flexible element whereby the joint between said members is rendered water-proof and dirt-proof.

12. In a device of the class described including a housing formed with a longitudinal slot and with a downturned flange at the rear margin of said slot and a roller mounted flexible element in said housing adapted to be extended through said slot, a binder strip attached to the free margin of said flexible element, said binder strip being formed with a rearwardly directed hooked portion, said binder strip adapted to extend partially within said housing and into engagement with the forward wall of said slot when the flexible element is completely retracted and with its hooked portion engaging behind the flange of the housing to completely close the slot therein.

13. In a device of the class described including a housing formed with a longitudinal slot and a roller mounted flexible element in said housing adapted to be extended through said slot, a metal binder strip attached to the free margin of said flexible element, an ornamental strip of flexible character, and means for detachably connecting said ornamental strip to the binder strip whereby the ornamental strip forms a continuation of the flexible element.

14. In a device of the class described, including a housing formed with a longitudinal slot and a roller mounted flexible element in said housing adapted to be extended through said slot, a metal binder strip attached to the free margin of said flexible element, an ornamental strip of flexible character, and attaching clips having tongues extending through the ornamental strip and through said binder strip, for detachably connecting the ornamental strip whereby it forms a continuation of the flexible element.

15. In a device of the class described, including a housing formed with a longitudi-

nal slot and a roller mounted flexible element in said housing adapted to be extended through said slot, a metal binder strip attached to the free margin of said flexible element, an ornamental strip of flexible character, and attaching clips having tongues extending through the ornamental strip and through said binder strip for detachably connecting the ornamental strip, whereby it forms a continuation of the flexible element, said attaching clips being mounted on the outer face of the ornamental strip and serving to engage the housing at one edge of the slot therein and thereby prevent contact of the ornamental strip with the housing.

16. In a device of the class described having a roller mounted flexible element and a U-shaped frame having its central portion engaging the free edge of said flexible element, pivotally mounted tubes adapted to receive the ends of said U-shaped frames for sliding movement, and cushioning springs mounted behind said pivoted tubes and having seats for engaging the same when the tubes are in substantially upright position, said seats being separable, whereby they may engage opposite sides of the tubes at times for supporting them in upright positions.

17. In a device of the class described including a roller mounted flexible element and a U-shaped frame engaging said flexible element and having a pivotal mounting to a structural frame, a draft element connected to each side of said U-shaped frame, pulleys mounted at the lower corners of the structural frame for receiving said draft elements, a single pulley housing at the lower central portion of the structural frame, and two pulleys mounted side by side in said housing to receive said draft elements, whereby said draft elements may be simultaneously employed for controlling the position of said flexible element.

18. In a device of the class described including a roller mounted flexible element and a U-shaped frame engaging said flexible element and having a pivotal mounting to a structural frame, a draft element connected to each side of said U-shaped frame, pulleys mounted at the lower corners of the structural frame for receiving said draft elements, a single pulley housing at the lower central portion of the structural frame, and two pulleys mounted side by side in said housing to receive said draft elements, said pulley housing being arched upwardly at its central portion to permit superposition of the draft elements therein, and a single pulley mounted rearwardly of said pulley housing for receiving both of said draft elements and provided with a fastening means therefor.
